BICYCLE

Glen R. Shaw, P.O. Box 179, Escalante, Utah 84726

Filed Mar. 10, 1970, Ser. No. 21,836

Term of patent 14 years

Int. Cl. D12—11

U.S. Cl. D90—8

FIG. 1 is a top perspective view taken from the right of a bicycle embodying my new design;

FIG. 2 is a side elevation view taken from the right of the bicycle of FIG. 1;

FIG. 3 is a side elevation view taken from the left of the bicycle of FIG. 1;

FIG. 4 is a front elevation view of the bicycle of FIG. 1; and

FIG. 5 is a rear elevation view of the bicycle of FIG. 1.

I claim:

The ornamental design for a bicycle, substantially as shown.
